CHARLES A. CANDA

INVENTOR.

BY *W. H. Berrigan*,
ATTORNEY.

UNITED STATES PATENT OFFICE.

CHARLES A. CANDA, OF ELIZABETH, NEW JERSEY.

TELLTALE FOR BOTTLES AND THE LIKE.

1,110,886.

Specification of Letters Patent. Patented Sept. 15, 1914.

Application filed July 15, 1913. Serial No. 779,132.

To all whom it may concern:

Be it known that I, CHARLES A. CANDA, a citizen of the United States of America, residing at Elizabeth, in the county of Union, 5 State of New Jersey, have invented a new and useful Improvement in Telltales for Bottles and the like; and I do hereby declare the following to be a full, clear, and exact description of the same.

10. This invention relates to tell-tale or indicating devices whereby the refilling of bottles, cans and the like may be detected, making pure food possible, and has for its object to provide an economical device of this kind 15 which will be entirely efficient and which will not require any special form of bottle or closure. To this end I have provided a tell-tale of aluminum or other suitable material, adapted to fit in the neck of any ordinary bottle, can or the like and when it is so placed it is under compression and is held in this position by its power to expand against the neck of the receptacle, and it is this force 20 under compression which holds it in place 25 in the neck of the receptacle.

The reason I prefer aluminum or other like material for the tell-tale is that this metal, as used, has sufficient elasticity to hold the tell-tale in the neck of the bottle, 30 but is so soft that it is very easily deformed and permanently distorted, as would be the case in attempting to withdraw the tell-tale through the neck of the bottle. Also aluminum tears easily and the thin fluted tell-tale is either permanently distorted or torn 35 in removing it, so that it cannot be used again without detection.

It is understood that I do not limit myself to the exact construction shown and 40 described, since the construction may be greatly varied without departing from the spirit and scope of the invention as defined in the appended claims.

In the accompanying drawing: Figure 1 45 is a vertical central sectional view of a receptacle closed with a crown seal and provided with the tell-tale, and Fig. 2 is a plan of the tell-tale.

The tell-tale 20 is shown inserted in the 50 smooth interior of the neck 21 having a crown-seal 22, but it is understood that it may be used with any normal form of neck or closure.

The tell-tale 20 consists of a sheet of alu-

minum or other suitable thin resilient material stamped to the shape illustrated, so as to provide fluted edges 25, the diameter of this tell-tale, at the fluted edge, being normally greater than that of the neck of the receptacle and adapted to be in a state of 60 compression when in the neck of the receptacle and to expand to a much larger diameter when forced down into the body of the receptacle.

The tell-tale 20 may be inserted to the 65 position illustrated or forced into the interior of the bottle by hand or any suitable device.

When the tell-tale 20 has been forced into the body of the receptacle for the purpose of 70 emptying the receptacle it cannot, without being permanently distorted or torn or otherwise destroyed, be again removed from the receptacle because it will expand to a diameter larger than the neck as stated 75 above, and it cannot be grasped, except at the edges, in which case the flaring bottom edge will catch in the upper part of the bottle and become wedged across the bottle neck, and thus be permanently distorted or 80 torn if an attempt be made to draw it through the bottle neck.

I claim as my invention:

1. In combination, a receptacle having a neck having a continuously smooth inner 85 face; and a slightly elastic, easily deformable flexible tell-tale placed in and directly engaging said neck and held in said neck by direct friction only and adapted when forced downwardly to expand to a diameter 90 larger than the neck and to be permanently deformed or torn if withdrawn through the neck.

2. In combination, a receptacle having an 95 interiorly smooth neck; and a one piece tell-tale comprising a thin slightly elastic sheet of flexible metal having a smooth continuous upper face and a long flaring skirt.

3. In combination, a receptacle having an 100 interiorly smooth neck; and a one piece tell-tale comprising a thin slightly elastic sheet of flexible metal having a smooth continuous upper face and a long flaring skirt, said tell-tale being relatively long in the direction of its axis and being easily permanently deformed.

4. In combination, a receptacle having an 105 interiorly smooth neck; and a one piece tell-

tale comprising a thin slightly elastic sheet
of flexible metal having a smooth continuous
upper face and a long flaring fluted skirt,
the limit of elasticity of said tell-tale being
5 slight so that when the tell-tale is consider-
ably deformed, it does not regain its ap-
proximate original shape.

In testimony whereof, I have signed my
name to this specification in the presence of
two subscribing witnesses.

CHARLES A. CANDA.
